UNITED STATES PATENT OFFICE.

JOHN NUTRY, OF BROOKLYN, NEW YORK.

INSTRUMENT FOR INDICATING AND RECORDING THE SPEED OF VEHICLES.

SPECIFICATION forming part of Letters Patent No. 702,110, dated June 10, 1902.

Application filed July 26, 1901. Serial No. 69,759. (No model.)

To all whom it may concern:

Be it known that I, JOHN NUTRY, a citizen of the United States, residing in Brooklyn, city and State of New York, have invented a new and useful Improvement in Instruments for Indicating and Recording the Speed of Vehicles, of which the following is a specification.

The object of this invention is to make an instrument that will exhibit plainly to the eye the rate of speed of the vehicle and also to make a permanent record of the speed and distance traveled.

The accompanying drawings, forming part of this specification, show the construction and arrangement of parts, in which—

Figure 1 is a section through the middle. Fig. 2 is an elevation of the speed-indicator portion. Fig. 3 is an elevation of the recording portion. Fig. 4 is an elevation of indicator-dial, reduced size. Fig. 5 is the ribbon on which record is made.

Like letters refer to like parts.

The instrument in the form as here shown is contained in a cylindrical case A in two sections A' and A². The driving-wheel S can be a sprocket, gear, or pulley on shaft S'. Section A' contains the mechanism for the indicator, and section A² the recording mechanism. In section A² is a compartment A³, containing a timepiece or clock-movement that operates the shaft A⁴, on which is a drum T' and disk T⁷, connected together and driven by frictional contact with the shaft A⁴. Fixed to the wall of compartment A³ is a plate T⁵, flush with the face of disk T⁷, on which is a stud to hold a spool for the supply of ribbon T. At the other end is a hinged arm T³, on which is a revolving disk T², the disk being held in contact with disk T⁷ by spring T⁴ pressing against the arm T³. The disk T² carries a spool on which the ribbon is wound after the record has been made on it. The ribbon T has a line of perforations T⁶, Fig. 5, and is marked for hours and portions of hours. The ribbon is placed in the instrument so that it passes over the drum T', the points on the drum entering the perforations in the ribbon, so that the ribbon moves at the speed of the drum, which in this case is one revolution in one hour. Fixed to the wall of compartment A³ is a bracket L⁵, and

hinged to it is a piece L⁴, so formed as to hold the ribbon onto the drum and slotted so as to allow the ribbon to be perforated by the needle L³. The cylinder A² can be hinged or otherwise made to separate from cylinder A' for the purpose of changing the record-ribbon. The needle L³ is connected to and operated by the mechanism in cylinder A'. It is fixed to lever L and held in position by spring L². The lever L is held in position by spring L' and is operated by a cam C on shaft W³, moving against a projection on lever L, the lever L being held in contact with the cam by spring L'. The shaft W³, on which the cam is fixed, is driven by worm-wheel W² and that by worm W' on shaft W, which is driven by worm-wheel S³ and worm S² on shaft S' and through wheel S, connected to a wheel of the vehicle, each revolution of the cam recording a definite distance traveled.

N is a support attached to the case, by which it can be fixed to the vehicle.

At one end of the cylindrical case is a dial 75 for showing the speed of the vehicle. Its face is of glass A⁵, with the dial D back of the glass and pointer D² between glass and dial.

D³ is the shaft, carrying the pointer and a pinion Q². Geared with the pinion is a quadrant Q, hung or pivoted on the front plate of cylinder A' and having arm Q' extending between collars on sleeve G³, which slides on shaft S'. Fixed to shaft S' is a hub and frame carrying arms and balls G, which are hung or pivoted at G' in the frame and having arms G² extending between collars on the sleeve G³.

F is a frame fixed into the cylinder-case A' for the support of shafts W' and D³. 90

The operation of the invention is as follows: The instrument is attached to a suitable part of the vehicle. The wheel S is geared so as to be driven at a determined ratio of speed from one of the wheels of the vehicle. The 95 balls G fly out by centrifugal force from the shaft S' to a degree proportionate to the speed of the vehicle and by the arms G² carry the sleeve along the shaft S' against a spring (not shown) of any suitable form and moves the quadrant Q in like proportion through the lever Q'. The quadrant being in gear with pinion Q² moves the shaft D³ and the pointer D² over the face of the dial to markings indicat-

ing speeds. Any change of speed of the vehicle will show a corresponding change in the position of the pointer on the dial. At the same time the shaft S' communicates motion 5 to the worm-wheel S³ on shaft W and by worm W' to worm-wheel W² on shaft W³.

Having described my invention, what I claim, and desire to secure by Letters Patent, is—

- 10 In an instrument for indicating and recording the speed of vehicles, a centrifugal governor with means for attaching to vehicle and suitable gearing to operate it from a wheel of the vehicle, a slide on the governor-shaft operated by the governor, a quadrant or section of a wheel connected to and moved by the slide, a pinion geared to and driven by 15 the quadrant, a pointer fixed to the pinion-

shaft and an index over which the pointer moves, a cam driven by gearing from the 20 governor-shaft, a lever arranged to be operated by the cam in one direction and by a spring in the opposite direction, a needle at the free end of the lever, a platen having a slot for the entrance of the needle; in combination with a drum driven by a clock-motion and arranged to carry a ribbon against the platen, the lever and needle being arranged to perforate the ribbon with a straight line of holes, substantially as shown and de- 25 scribed.

JOHN NUTRY.
